ATTORNEY

UNITED STATES PATENT OFFICE

DAVID McALLISTER, OF SEATTLE, WASHINGTON, ASSIGNOR TO AMERICAN MACHINE & FOUNDRY COMPANY, A CORPORATION OF NEW JERSEY

SLICED BREAD TRANSFER

Application filed February 25, 1932. Serial No. 595,182.

This invention relates to a transfer device for guiding sliced articles such as loaves of bread from a bread slicing machine to a wrapping machine, its main object being to automatically bridge, for the passage of each loaf, the gap between the end of the delivery table of the slicing machine and the receiving runway of the wrapping machine. The said gap being required for the passage of the delivery pushers of the slicing machine which are usually attached to endless chains, a narrow rectangular or a round loaf would drop into the gap between the delivery table and the receiving runway of the wrapping machine and would thus be damaged if no supporting bridge were provided. With this and other objects not specifically mentioned in view, the invention consists in certain constructions and combinations hereinafter 20 fully described and then specifically set forth in the claims hereunto appended.

The transfer bridge in the present invention is hinged to the end of the receiving runway of the bread-wrapping machine and held 25 in alignment with the same by a spring in such a manner that each pusher, after delivering the loaf over the transfer bridge onto the wrapping machine runway, will depress the bridge by its own motion, the spring, after the passing of the pusher, automatically replacing the bridge into transfer position for the next on-coming loaf.

In the accompanying drawing which forms a part of this specification and in which like 35 characters of reference indicate the same or like parts,

Fig. 1 is a side elevation showing the end of the delivery table of slicing machine placed in proper working relation to the receiving runway of a bread-wrapping machine, the latter being provided with the improved transfer bridge; and

Fig. 2 is a top view of the mechanism shown in Fig. 1, seen from line 2—2 of the same.

In carrying the invention into effect there is provided a delivery table, endless chain conveyors having pushers for forwarding the articles along said table, a delivery runway 50 adjacent the delivery end of said table to

which the articles are forwarded, said runway being spaced from the table to provide a gap for the passage of the pushers, and means movable into and out of the path of the pushers for bridging said gap. In the best forms of construction contemplated said means includes a transfer bridge, a cross rod on which said bridge is fixed and a tension spring connected to the cross rod to yieldingly hold the bridge in article guiding position. These various means and parts may be widely varied in construction within the scope of the claims, for the particular device selected to illustrate the invention is but one of many possible concrete embodiments of the same. The invention, therefore, is not to be restricted to the specific construction shown and described.

Referring to the drawing, the sliced loaf L, which is shown of cylindrical shape, is delivered from the slicing machine on a delivery table 10 by pushers 11 which propel the loaf across a gap-closing plate or bridge 12 onto an inclined runway 13 of the wrapping machine. The pushers 11 are attached across two parallel endless chains 14 running over sprockets 15 mounted on a cross shaft 16 carried by side frames 17 of the slicing machine. The gap closing plate 12 is fastened to a cross rod 18 carried by bearings 19 attached to a support 20 of the wrapping machine.

The pushers 11, at the end of their forward travel, turn around the sprockets 15, thereby gradually forcing the gap bridge 12 to its downmost position 12' (dotted lines) 25 when the pusher 11 is in its dotted position 11'. The bridge 12, in so moving, turns the cross rod 18 so that its flattened downwardly bent end 21 moves to the dotted position 21', thereby stretching a tension spring 22 which normally holds the bridge 12 in alignment with runway 13 against a stop 23 engaging the bent end 21. The spring 22 is fastened to the bent end 21 and has its other end anchored to a post 24 carried by the frame 17. 95 The pusher 11, in leaving the path of the bridge 12, sets the same free, permitting the spring 22 to pull it back to its former position against the stop 23.

The loaf L is delivered crosswise onto

runway 13 and, when arrived in position L' against the side wall 26, enters between a pair of clamps 25, adjusted to the length of the loaves, which hold the slices together to prevent them from being disarranged. The clamps 25, which are arranged in pairs on endless chains, propel the loaf L' lengthwise into the folding mechanism of the wrapping machine.

10 What is claimed is:

1. The combination with a table, of conveyor chains extending along said table, pushers extending across said table and fixed on by said chains, a delivery runway extending transversely of said table and spaced therefrom, a transfer bridge disposed between the delivery end of said table and said runway to guide articles forwarded by said pushers onto said runway, and means yieldingly supporting said bridge to permit the passage of said pushers beyond the delivery end of said table when they engage said bridge.

2. The combination with a table, of conveyor chains extending along said table, pushers extending across said table and fixed on by said chains, a delivery runway extending transversely of said table and spaced therefrom, a transfer bridge disposed between the delivery end of said table and said runway to guide articles forwarded by said pushers onto said runway, and means yieldingly supporting said bridge to permit the passage of said pushers beyond the delivery end of said table when they engage said bridge, said means including a cross rod on which said bridge is fixed, said rod having one of its ends bent downwardly, a tension spring connected to the downwardly bent end of said rod, and a stop engaging said downwardly bent end to hold said bridge in article guiding position against the tension of said spring.

3. In a loaf transfer, the combination with a table, of an endless chain conveyor having pushers for forwarding the loaves sidewise along said table, a runway adjacent one end of said conveyor to which the loaves are forwarded, said runway being spaced from the end of the table to provide a gap for passage of the pushers, and means movable into and out of the path of said pushers for bridging said gap.

4. In a loaf transfer, the combination with a table, of an endless chain conveyor having pushers for forwarding the loaves sidewise along said table, a runway adjacent one end of said conveyor to which the loaves are forwarded, said runway being spaced from the end of the table to provide a gap for passage of the pushers, and means movable into and out of the path of said pushers for bridging said gap, said means including a movably mounted plate, and mechanism yieldingly urging said plate into gap bridging position.

5. In a loaf transfer, the combination with a table, of an endless chain conveyor having pushers for forwarding the loaves sidewise along said table, a runway adjacent one end of said conveyor to which the loaves are forwarded, said runway being spaced from the end of the table to provide a gap for passage of the pushers, and means movable into and out of the path of said pushers for bridging said gap, said means including a movably mounted plate, and mechanism yieldingly urging said plate into gap bridging position, and said pushers coasting with said plate to push the latter out of the path of the pushers against the action of said mechanism.

In testimony whereof, I have signed my name to this specification.

DAVID McALLISTER.
